United States Patent [19]

Kemnitz

[11] Patent Number: Des. 352,411

[45] Date of Patent: ** Nov. 15, 1994

[54] **PANEL FOR PATIO FURNITURE**[75] Inventor: **Glen D. Kemnitz**, Gallatin, Tenn.[73] Assignee: **Sunbeam Corporation**, Fort Lauderdale, Fla.[**] Term: **14 Years**[21] Appl. No.: **2,049**[22] Filed: **Nov. 30, 1992**3,590,901 5/1969 Dubinsky ..... 297/452.63 X
3,751,110 8/1973 Shaw ..... 297/452.63*Primary Examiner*—Janice E. Seeger*Attorney, Agent, or Firm*—Michael J. Kline; Darren E. Wolf[57] **CLAIM**

The ornamental design for panel for patio furniture, as shown and described.

DESCRIPTION

FIG. 1 is a perspective view of a panel for patio furniture, showing my new design, with the edges wrapped in condition for use; the broken lines are for environmental purposes only and form no part of the claimed design;

FIG. 2 is a front elevational view of the panel;

FIG. 3 is a rear elevational view of the panel;

FIG. 4 is a top plan view of the panel;

FIG. 5 is a bottom plan view of the panel;

FIG. 6 is a left side elevational view of the panel; and,

FIG. 7 is a right side elevational view of the panel.
